US0D1074903S

(12) **United States Design Patent** (10) **Patent No.:** **US D1,074,903 S**
(45) **Date of Patent:** **** May 13, 2025**

(54) **RECREATIONAL WATER DEVICE**

(71) Applicant: **Wibit Sports GmbH**, Bocholt (DE)

(72) Inventors: **Romann Rademacher**, Bocholt (DE);
Robert Cirjak, Bocholt (DE)

(**) Term: **15 Years**

(21) Appl. No.: **35/521,060**

(22) Filed: **Mar. 22, 2024**

(80) **Hague Agreement Data**

Int. Filing Date: **Mar. 22, 2024**

Int. Reg. No.: **DM/237191**

Int. Reg. Date: **Mar. 22, 2024**

Int. Reg. Pub. Date: **May 31, 2024**

(30) **Foreign Application Priority Data**

Sep. 26, 2023 (EM) 015035214-0009

(51) **LOC (15) Cl.** **21-03**

(52) **U.S. Cl.**
